CLAIM

The ornamental design for a chemical mixing container for sprinklers, as shown and described.

DESCRIPTION

FIG. 1 is a perspective view of a chemical mixing container for sprinklers showing my new design; FIG. 2 is a front elevational view thereof, the rear view being a mirror image;

FIG. 3 is an end elevational view thereof;

FIG. 4 is an opposite end elevational view thereof;

FIG. 5 is a top plan view thereof; and,

FIG. 6 is a bottom plan view thereof.

FIG. 1

FIG. 2

FIG. 4

FIG. 3

FIG. 6

FIG. 5
